[57] CLAIM

We claim the ornamental design for a garden tool, as shown.

DESCRIPTION

FIG. 1 is an oblique perspective view of a preferred embodiment of our design for a garden tool;

FIG. 2 is an enlarged front elevation thereof;

FIG. 3 is a rear elevation thereof;

FIG. 4 is a left side elevation thereof;

FIG. 5 is a right side elevation thereof;

FIG. 6 is a top plan view thereof; and,

FIG. 7 is a bottom view thereof.

The handle of the tool is shown fragmented in FIGS. 2-5 for clarity of illustration.
